UNITED STATES PATENT OFFICE.

ARTHUR HENRY BARKER, OF WESTMINSTER, LONDON, ENGLAND.

HEATING AND COOLING DEVICE FOR BUILDINGS.

Application filed November 23, 1926, Serial No. 150,304, and in Great Britain December 4, 1925.

This invention relates to heating and cooling devices for buildings, said devices being of the kind that are generally known as radiators and that comprise flat or substantially flat metal plates having passages extending through them for the heating or cooling medium or fluid and adapted to be applied to a wall in such manner that the heat is radiated into the building from the exposed outer surface of the plates without undue heat losses at the back.

According to my invention the improved radiator has a flat or substantially flat metal heat radiating surface or plate with passages or channels for the heating medium or fluid and with a rib or flange at its back to constitute the marginal boundary of a space immediately behind it. The said heat radiating surface or plate is composed of some inexpensive metal such as cast iron or rolled steel having only a relatively few heating passages or channels spaced widely apart and well away from the marginal edge of said surface or plate (except at the inflow and outflow connections) and with flat or substantially flat webs between them of considerably greater area than the exposed area of the said passages or channels thereby affording a better or more uniform distribution of temperature than heretofore over a large surface for radiation which therefore need only be heated to a relatively low temperature (say about 90° F.). The arrangement of the heating passages or channels so that they are spaced widely apart and well away from the marginal edge of the plate, as aforesaid, is suitable for plain plates as well as for the ribbed or flanged plates. In order further to conserve the heat at the surface of radiation I prefer to provide at the back of the aforesaid space, a sheet plate or lining of tin, copper, brass or other appropriate material, highly polished on its surface facing the heat radiating plate so as to act as an internal heat reflector; or a sheet plate or lining of a poor heat conducting character such for instance as hair felt mounted on a backing of metal or other suitable material may be used instead of the heat reflecting plate. The heat radiating plate may be secured to the said heat reflecting or heat non-conducting plate in such manner that the enclosed space between them is air-tight or approximately air-tight and for this purpose the aforesaid marginal rib or flange may be rendered true on its

face so that a reasonably good fit can be made between the aforesaid heat reflecting or non-conducting plate and the heat radiating plate, or between the wall and the heat radiating plate when the aforesaid heat reflecting or non-conducting plate is not employed.

The said heat radiating plate with its heating passages or channels and the marginal rib or flange are preferably formed as one casting, the aforesaid heat reflecting or non-conducting plate being detachably connected to the marginal rib or flange by any suitable means and in this case the radiator constitutes a self-contained unit which if desired may be used for standing on the floor and close to the wall of the room to be heated.

The said passages or channels may be attached to the heat radiating plate instead of being formed integral therewith and may be used for the conveyance of hot water or steam or for the accommodation of electrical heating conductor members or elements.

When large heat radiating surfaces are required the heat radiating plate may be built up in sections of any desired dimensions which are secured together to form a continuous heat radiating surface in any appropriate manner, as for example by junctions of suitable form between the aforesaid passages or channels.

To heat the radiator electrically I introduce into some or all of the heating channels or passages of the heat radiating plates electric heating elements of any appropriate kind which are so arranged as to supply heat directly to said channels or passages, that is to say without the intervention of a fluid (water) circulating through the channels or passages in which the electric heating elements are disposed. In some cases however the radiator may be adapted to be heated alternatively by electricity or by steam or hot water at the will of the user, in which case some of the heating channels or passages would be used for the circulation of the steam or hot water and others (through which no steam or hot water passes) would be provided with the electric heating elements, the electric current for the latter being switched on and off as required, it being understood that when the steam or hot water is being used, the electric heating elements would be cut off and when the elec-

tric heating elements are being used the steam or hot water would be cut off, unless an extra amount of heat were required on certain occasions when both the steam or hot water and the electric heating elements would be employed at the same time.

In the accompanying drawings:—

Figure 1 is a front elevation and

10 Figures 2, 3 and 4 are sections taken respectively on the lines 2—2, 3—3 and 4—4 of Figure 1, showing the improved radiator in the form of a self-contained unit adapted to be placed against or contiguous to the wall of a room.

15 Figure 5 is a front elevation and

Figures 6, 7, 8 and 8^a are sections taken respectively on the lines 6—6, 7—7, 8—8 and 8^a—8^a of Figure 5 showing the radiator built up in sections or elements and adapted 20 to be affixed to the wall or ceiling of a room.

Figure 9 is a vertical section (similar to Figure 6) showing the radiator adapted to be countersunk into a cavity formed for its reception in the wall or ceiling.

25 Figure 10 illustrates on a smaller scale than the other figures one form of the heat non-conducting plate.

Figure 11 is a front elevation of a radiator similar to that shown by Figure 5 adapted 30 to be heated electrically.

Figure 12 is a longitudinal section on a larger scale taken through one of the longitudinal passages or channels showing a convenient form of electric heating member in 35 place therein.

Figure 13 is a longitudinal section similar to Figure 12, and

40 Figure 14 is a cross section taken on the line 14—14 of Figure 13, showing a modified form of electric heating member.

Like letters of reference indicate similar parts in all the figures.

45 A is the heat radiating plate and *a*, *a* are the passages or channels therein for the heating medium or fluid, these passages or channels extending longitudinally and transversely and being as shown, few in number, spaced widely apart and well away from the marginal edge of said plate except at the

50 parts where they necessarily extend to the edge to reach the inflow and outflow connections. *a*¹ is the rib or flange at the back of the plate A constituting the marginal boundary of the space B which is situated

55 immediately behind the heat radiating plate A and which is such that the external air cannot pass or circulate over the back of the said plate. C is the heat reflecting plate constituting the back of the space B and

60 having its inner surface highly polished to act as a reflector for directing the heat inwardly and restraining it from being conducted away through the back of the radiator. The marginal rib or flange *a*¹ has a 65 depth equal to that of the space B and to

this flange the heat reflecting plate C is detachably secured by means of screws *c* engaging with internal lugs *a*² on the plate A, the edge of the flange being rendered true by machining or otherwise so that an air-tight 70 or approximately air-tight connection between the plate C and the flange *a*¹ can be obtained, the radiator thus constituting a self-contained unit. In Figures 1 to 4 the heat radiating plate A is provided with 75 flanged brackets or feet *a*³, *a*³ for supporting the radiator vertically on the floor, screws or other means of attachment being employed for securing it firmly in place in proximity to a wall.

In cases where large radiating surfaces are to be provided, the radiator may be built up in sections as shown by way of example in Figures 5, 6, 7, 8 and 8^a where three heat radiating plates are employed, viz:—two end plates and an intermediate plate. In this case each section may have a marginal rib or flange *a*¹ extending all round it as shown at Figure 5 so that each section has its own independent space or the end sections may have their outer ends and sides flanged and the intermediate section may have only its sides flanged so that when the various sections are assembled the flanges will meet together and extend completely around the 90 margin of the sectional structure and provide a space common to all the sections. The longitudinal channels or passages of the heat radiating plates are formed at their meeting ends or junctions with screw threaded sockets *a*⁴ with which correspondingly screw threaded hollow plugs engage for securely connecting the sections together and rendering the joints at the junctions fluid-tight. The said radiator may be held in place 95 against the wall or ceiling of a room by means of coach screws *a*⁵ engaging with plugs *a*⁶ in the wall or ceiling, the heads of the screws being in the example shown (Figure 7) countersunk into the outer surface of the heat radiating plates A. When the heat radiating plates are to be used in sectional or built up form, that is to say with the sections attached together at their meeting edges and with their heating passages in register, the 100 aforesaid marginal flanges may in some cases be dispensed with.

105 Instead of employing the heat reflecting plate C at the back of the enclosed space B I may employ a heat non-conducting member composed for example of a sheet of hair felt *b* (Figure 10) attached to the surface of a plate by a marginal frame *b*¹ screwed thereto.

110 In Figure 9 the radiator is shown countersunk into a recess formed for its reception in the wall E, the said recess being of a depth equal to that of the flange *a*¹ of the heat radiating plate A. Under certain circumstances as for instance where the wall 115

at the back of the recess is a division wall between two rooms to be heated the aforesaid heat reflecting or heat non-conducting plate may be dispensed with.

5. Figure 12 and Figures 13 and 14 illustrate two examples suitable for use when the radiator is to be heated electrically, said elements consisting of a central cylinder or core F of asbestos or other insulating material wound around or provided with an electric conductor in the form of a coil f having terminals f¹, f² for connection to a source of electric supply and surrounded by a tubular member or support a^o which is heated by the said element. This tubular member or support a^o may be constituted by the walls of said channels or passages of the heat radiating plate A into which the said elements are introduced as in Figure 20 in which case washers, spiders or the like F³ composed of asbestos or other insulating material are provided around the central cylinder or core F and its surrounding coil f to act as distance pieces for spacing said coil from the surrounding wall a^o of the channels or passages. The terminals f¹, f² may be mounted on insulating plates f³ countersunk in the sockets a⁴ of the channels or passages. These plates may be situated at each end of the coil to enable one heating element to be connected to another in series if they are employed in separate lengths or if they be composed of a single length as indicated in Figure 11 both terminals will be at one end as in Figures 12 and 13 and the central cylinder or core then might be made hollow, as shown in those figures, and a metal rod F⁴ (Figure 12) inserted therein, the end of the coil f remote from the terminal plate f³ being connected to the corresponding end of the rod F⁴ and the terminal f² being connected to the other end while the other terminal f¹ would be connected to the adjacent end of the coil f. 45 Instead of employing a metal rod, one end of the coil f may extend through the hollow cylinder or core to reach one of the terminals as shown at Figure 13. Also instead of employing the washers spiders or the like F³ to serve as insulating distance pieces, I may employ an insulated tube F² surrounding the coil f and fitting against the inner surface of the surrounding wall a^o of the heating channels or passages. 55 If the heating elements are to be employed on an alternating current circuit they may be made in such a manner that metal enters largely into their construction, so that a portion of the heat generated thereby arises from eddy currents generated in the metal portions by the alternating flux. This effect may be augmented by employing iron or other magnetic material for the aforesaid metal portions. Thus, the tubular member or support a^o surrounding the coil f and its core F¹ and the central rod F⁴, in the case in which such a rod is employed, may be of magnetic material (as it would be when constituting the wall of the channels or passages in the heat radiating plate A) and, further, the ends of the heating element may be fitted with washers or discs of magnetic material in contact with both the tubular member or support a^o and the rod F⁴ in order to complete the magnetic circuit. 70 When the radiator is adapted to be heated alternatively by electricity or by steam or hot water, the transverse channels or passages a communicating with the longitudinal channels or passages would be of semi-circular cross-section and stopped off from the longitudinal channels or passages at the places indicated by the dotted lines a²⁰ in Figure 11 in order to prevent the steam or hot water from reaching the electric heating elements while rendering the said steam or hot water free to circulate in its own independent system. 80 Although I have described my improved radiator more particularly for use as a heating device it may also be used in certain cases as a cooling device and therefore the term "radiator" used in the description and claims is intended to embody either of these uses in connection with buildings and other structures. I also wish it to be understood that while I have described my improved radiator more particularly for use in connection with a wall it is also intended to be used with a ceiling and therefore when I refer in the claims to the "wall" I intend to include the ceiling; the "wall" is also intended to include a plurality of walls. Also, when I refer in the claims to a "plate" I intend to include a plurality of plates and 95 when I refer to "circulating passages" I intend to include a single passage in those cases where its use would be practicable. 100 What I claim and desire to secure by Letters Patent of the United States is:— 110
1. A radiator for heating buildings consisting of a metal plate adapted to be fixed to the wall of the room to be heated and having a flat or substantially flat and extensive heat radiating surface with circulating 115 passages for the heating medium and a flange at the back to constitute the marginal boundary of a space closed to the flow of the external air over the back of the plate. 120
  2. A radiator for heating buildings consisting of a metal plate adapted to be fixed to the wall of the room to be heated and having a flat or substantially flat and extensive heat radiating surface with circulating 125 passages for the heating medium and a flange at the back to constitute the marginal boundary of a space behind said plate, and means for opposing the transmission of heat through the back boundary of said space. 130
  3. A radiator for heating buildings con-

- sisting of a metal plate adapted to be fixed to the wall of the room to be heated and having a flat or substantially flat and extensive heat radiating surface with circulating passages for the heating medium and a flange at the back to constitute the marginal boundary of a space behind said plate provided at the back with a heat reflector.
4. A radiator for heating buildings consisting of a metal plate adapted to be fixed to the wall of the room to be heated and having a flat or substantially flat and extensive heat radiating surface with circulating passages for the heating medium and a flange at the back to constitute the marginal boundary of a space behind said plate provided at the back with a detachable plate having a highly polished inner surface.
5. A radiator for heating buildings consisting of a metal plate adapted to be fixed to the wall of the room to be heated and having a flat or substantially flat and extensive heat radiating surface with circulating passages for the heating medium and a flange at the back to constitute the marginal boundary of a space behind said plate provided at the back with a heat non-conducting surface.
6. A radiator for heating buildings consisting of a metal plate having a flat or substantially flat and extensive heat radiating surface with circulating passages for the heating medium and a space bounded at the front by said plate, at the sides and ends by a marginal flange and at the back by a heat opposing element, the whole constituting a self-contained unit adapted to be placed against or contiguous to the wall of the room to be heated.
7. A radiator for heating buildings consisting of a metal plate adapted to be fixed to the wall of the room to be heated and having a flat or substantially flat and extensive heat radiating surface with cross-connected longitudinal and transverse circulating passages for the heating medium placed well apart and well away from the marginal edge of the plate and a flange at the back to constitute the marginal boundary of a space behind said plate.
8. A radiator for heating buildings consisting of a built up metal plate adapted to be fixed to the wall of the room to be heated with its sections edge to edge and having a flat or substantially flat and extensive heat radiating surface with longitudinal and transverse circulating passages for the heating medium, a flange at the back of said sections to constitute the marginal boundary of a space behind said plate when built up and means for attaching said sections together at their meeting edges with their longitudinal passages in register.
9. A radiator for heating buildings consisting of a metal plate adapted to be fixed
- to the wall of the room to be heated and having a flat or substantially flat and extensive heat radiating surface with heating passages and electric heating elements in said passages for supplying heat directly thereto.
10. A radiator for heating buildings consisting of a metal plate adapted to be fixed to the wall of the room to be heated and having a flat or substantially flat and extensive heat radiating surface with heating passages of which some serve as conduits for a heating fluid and others for the reception of electric heating elements that are inaccessible to the heating fluid, said heating fluid and said electric heating elements being under control in such manner that either or both of them may be brought into action at will.
11. A radiator for heating buildings consisting of a metal plate adapted to be fixed to the wall of the room to be heated and having a flat or substantially flat and extensive heat radiating surface with heating passages, a flange at the back to constitute the marginal boundary of a space behind said plate and electric heating elements in said passages.
12. A radiator for heating buildings consisting of a metal plate adapted to be fixed to the wall of the room to be heated and having a flat or substantially flat and extensive heat radiating surface with circulating passages for the heating medium placed well apart and well away from the marginal edge of the plate.
13. A radiator for heating buildings consisting of a metal plate adapted to be fixed to the wall of the room to be heated and having a flat or substantially flat and extensive heat radiating surface with cross-connected longitudinal and transverse circulating passages for the heating medium placed well apart and well away from the marginal edge of the plate.
14. A radiator for heating buildings consisting of sectional metal plates adapted to be fixed to the wall of the room to be heated edge to edge each having a flat or substantially flat and extensive heat radiating surface with circulating passages for the heating medium and means for connecting said sections together with their passages in register.
15. A radiator for heating buildings consisting of sectional metal plates adapted to be fixed to the wall of the room to be heated edge to edge each having a flat or substantially flat and extensive heat radiation surface with cross-connected longitudinal and transverse circulating passages for the heating medium and means for connecting said sections together with their longitudinal passages in register.
16. A radiator for heating buildings con-

- sisting of a built-up metal plate adapted to be fixed to the wall of the room to be heated with its sections edge to edge and having a flat or substantially flat and extensive heat radiating surface with circulating passages for the heating medium, a flange at the back of said sections to constitute the marginal boundary of a space behind said plate when built up and means for attaching said sections together at their meeting edges with their passages in register. 17. A radiator for heating buildings consisting of a built-up metal plate adapted to be fixed to the wall of a room to be heated with its sections edge to edge and having a flat or substantially flat and extensive heat radiating surface with circulating passages for the heating medium, a flange at the back of said sections to constitute the marginal boundary of a space behind each section and means for attaching the marginally flanged sections together at their meeting edges with their passages in register. 18. A radiator for heating buildings consisting of a built-up metal plate adapted to be fixed to the wall of the room to be heated with its sections edge to edge and having a flat or substantially flat and extensive heat radiating surface with longitudinal and transverse circulating passages for the heating medium, a flange at the back of said sections to constitute the marginal boundary of a space behind each section and means for attaching the marginally flanged sections together at their meeting edges with their longitudinal passages in register. 20 25 30 35

ARTHUR HENRY BARKER.
